Letters Patent

The Schedule is referred to in these Letters Patent and making part of the same, containing a description in the words of the said Hiram Strait himself of his improvement in the construction and operation of valves on the principle of a Balance.

To all to whom these presents shall come. Be it known that I, Hiram Strait, of East River, in the County of Richmond and State of New York, have invented a new and useful improvement in the construction, application and operation of valves, on the principle of a Balance for the purpose of pressuring, compressing and releasing air and water, and that the following is a full and exact description of the construction, application and operation of valves on the said principle of a Balance as invented by me.

A represents the model to illustrate the construction, application and operation of valves on the principle of a Balance, to create a powerful precession on air. m. m. o. o. r. represents its sides which are four, of equal length and strongly joined together at their corners. o. o. represents its balancing centre or axle, which is strongly connected to the middle of the sides, o. m. These small horizontal lines drawn from o. to m. parallel to the axle, o. o. represent small wires woven through the sides. o. o. represent a thin narrow stiff strip of light cloth, paper or metal a little wider than to fill one interstice between those wires, and as long as m. or. o. This strip o. o. is to be neatly balanced & morally hung across the line, m. o. The heavier side is caused to hang down and be restrained so as to open at any angle by means of the strings, C.C. which are attached to the side, m. These are to be similarly hung on all the small parallel wires and restrained by strings, C.C.C.C. When this is done the handle, H, which is the common handle to operate the different modifications of the same principle in the model is to be moved quickly up and down which will cause a constant and powerful precession on the air, and consequently reaction which will either propel or draw up the valve horizontally or perpendicular. The strips, may like wires be hung by one of the long sides and so balanced, though more easily restrained. When the handle, H is raised all the valves between m. and o. o. blow air tight and strike the air while those between o. and o. o. open and let the incoming air through, when brought down, those that close open and those that open close so that it will strike the same one way as the other. The size, weight and shape of the wings to create precession hang on this principle of balance on vessels, but the principle of operation the same. This was for which I claim the aforesaid illustrations of the

987

principle of a Balance as an illustration and its application to the theory and practice of aerial marine and submarine navigation to the propagation of cars on Rail Roads, Canal Boats, Wind Ships, and Water-taxis. B. Fig. 2° represents the model to illustrate the construction, application and operation of valves on the principle of a balance, for the purpose of condensing or compressing and heating air. It. y. h. g. represent a strong plank which is balanced and evenly hung in the bottom of an airtight air cistern. The cistern and plank may be of any shape and size, but its bottom must come to a point or ridge to resemble an inverted roof. Along this ridge this plank is balanced, so that its sides h and k will alternately strike on each side of the ridge, or the bottom may be flat and then this plank must be caused to rest at its centre so as to allow the balancing motion. t. b. represent its axle in the middle when it is balanced across the bottom of the cistern.

V. W. represent two valves of a sufficient size one on each side of the balancing point which are to open upward as far as necessary for the easy admission of air. Valves being made and hung in the bottom of the air cistern, directly ^{having} over the balancing plank, and double their dimensions, so as to open sufficiently inward. The bottom of the cistern on each side the ridge is to be air tightly fastened by leather to this balancing plank, so as to allow its motion, and then when the double handle H is either raised or depressed it will draw as much air into the air cistern by an upward or downward motion. When the handle H is raised the valve W on the plank opens and lets in air, while the valve V closes tight and forces the air between it and the cistern through its own valve into it while when brought down, the valve V opens to let in air, and the valve W forces air into the cistern. The top of the air cistern can be made by means of leather to settle or fall as far into the cistern as it rises above and thus keep up the heat when the motion has ceased for some time according to the dimensions of the cistern. The uses for which I claim this valuable illustration of the principle of a Balance as a model, are its application to heating and the condensation or compression of air, either for the purpose of a moving power or explosion.

C. Fig. 3° represents a model to illustrate the construction, application and operation of valves on the principle of a Balance, for the purpose of admitting or pumping air from airtight reservoirs of any shape or size. The construction, application and operation are the same as those described on Figure 2°, only that the valves instead of opening inward and outward, b. d. f. represent the balancing plank, 2. 3. to act as a balancing point, and a. b. c. M. the valves which are hung directly under those in the

113
883 X

bottom of the reservoir to be exhausted of air. The uses for which I claim this valuable illustration of the principle of a Balance as an Inventor are its application to the exhausting of air from all kinds of reservoirs either for practical or scientific purposes.

④ Figure 4th represents the model to illustrate the construction application and operation of valves on the principle of a Balance for the purpose of pumping raising and compressing water &c &c &c uproot the screw to which the two piston Rods are attached on the lower ends of which the valves are hung either on a Balance or laterally. g.g. represent the balancing point or centre of the screw. XX represent the upper surfaces of two hollow tubes or pipes whose lower extremities are inserted into a body of water. When the handle H is raised the piston that operates in the orifice X. will raise the water over its valve. as that will immediately close while that in X opens to let the water up and thus whether the handle H is raised or depressed it will raise or pump as much water as can upward or downward motion. Any number of valves may be balanced and operate on this principle with ease and facility. The uses for which I claim this valuable illustration on the principle of a Balance as an inventor. are its application to raising pumping and compressing water for all practical purposes either for ships, wells, vessels, boats. Steam engines, fountains, and to the motion of machinery propelled by water.

⑤ Figure 5th represents the model to illustrate the construction, application and operation of valves on the principle of a balance, so as to create a powerful pressure either by water or air. a.b. c. d. represent on the balance beam. m.m. its first oracle across which it is balanced. S.T represent a valve through which the air or water is to pass in order to create the pressure. The balancing valves are to be heavy and have others hung on them. the same as in figure 2nd. The pressure will be communicated both by the upward & downward motion of the handle H. and can be either uniform or intermittent.

The uses for which I claim this valuable illustration of the principle of a Balance as an Inventor are. its application to printing stamping raising weights & the communication of all kinds of impressions. Therefore illustrations of the construction application & operation of valves on the principle of a balance can be operated by any moving power
